UNITED STATES PATENT OFFICE.

CLARENCE A. SPRAGUE, OF EAST ORANGE, NEW JERSEY, ASSIGNOR TO WESTERN ELECTRIC COMPANY, INCORPORATED, OF NEW YORK, N. Y., A CORPORATION OF NEW YORK.

OSCILLATION GENERATOR.

Application filed January 13, 1922. Serial No. 528,905.

This invention relates to generators of electric oscillations and more particularly to generators in which continuous oscillations are produced by periodically applying an electric impulse to a resonant circuit.

One object of the invention is to generate electric oscillations at high efficiency.

In accordance with the present invention electric oscillations are generated by a vacuum tube amplifier of the space current type. A highly negative polarizing potential on the grid of the tube tends to prevent the flow of any substantial amount of space current through the tube. A complex control wave having a component of fundamental frequency and a component of three times the fundamental frequency in proper phase relation is impressed upon the grid to suddenly render the tube highly conductive to space current and then suddenly return the tube to its original non-conducting condition. In this manner direct current from the space current source is efficiently converted into alternating current. A tuned circuit resonant to waves of fundamental frequency is coupled to the output circuit of the amplifier to select the wave of desired frequency therefrom.

Instead of employing a single tube, two tubes may be used, arranged as a balanced amplifier and having the space current normally blocked by a highly negative grid potential. The complex control wave described above is impressed upon the grids of the amplifier. In this case an impulse is produced alternately in the output circuit of one of said tubes and then in the output circuit of the other tube, thus providing two impulses for each cycle of the fundamental wave. The amplitude of the oscillations set up in the tuned circuit coupled to the balanced amplifier output circuit is maintained more constant than the amplitude of oscillations set up in a tuned circuit by only a single impulse during each cycle. On account of the generated wave being replenished with energy twice during each cycle, the ratio of fundamental to harmonic wave energy in a circuit containing a load is greater than in the case where only a single impulse occurs during each cycle. By providing one or more feed-back

circuits between the input and output circuits of a balanced amplifier, oscillations may be generated in accordance with this invention by regenerative action.

Other objects of the invention will be apparent from the more detailed description of the invention which follows taken in view of the appended drawing and claims.

Fig. 1 is a circuit diagram illustrating a simple form of the invention employing a single amplifier tube to generate oscillations; Fig. 2 is a graph illustrating the wave form of the complex control wave applied to the grid of the amplifier; Fig. 3 is a circuit diagram illustrating an oscillation generator employing a balanced amplifier; Fig. 4 is a circuit diagram of a balanced amplifier provided with a feed-back circuit to generate oscillations by regenerative action; Fig. 5, which is similar to Fig. 4, shows a circuit diagram in which two feed-back circuits are provided.

Referring to Fig. 1, the source of electric waves of fundamental frequency 1 is associated by means of the transformer or inductive coupling 2 with the harmonic producer or wave distorting device 3 which produces a wave having a component of fundamental frequency f , and a component of second harmonic frequency $3f$, having a frequency three times that of the fundamental frequency. The device 3 may be any well-known type of distorting device which is adapted to operate in response to an impressed wave to distort said wave and produce a second harmonic thereof. These fundamental and harmonic waves, combined in the form of a complex control wave, are transmitted through the inductive coupling or transformer 4 to the input circuit 5 of the amplifier tube 6 of the well-known space current type having a source of polarizing E. M. F. 7, in the input circuit 5 to apply a high negative potential to the grid 8 to prevent the flow of any substantial amount of space current from the source 9 in the output circuit 10.

Variations of current or impulses in the output circuit 10 are transmitted by means of an inductive coupling or transformer 11 to the tuned circuit 12 including the inductance 13 and the capacity 14 as well as inductance and capacity effectively in said cir-

cuit by virtue of the coupling 11, the connected load or other associated circuits which may be coupled with the circuit 12. The circuit 12 is adjusted to be of minimum impedance to the wave of fundamental frequency f . Resistance 15 represents the load through which the waves in the circuit 12 pass. The source of space current 9 is preferably made large in order to provide a large flow of current during the brief period when space current flows through the output circuit 10.

In Fig. 2, the ordinates represent grid potentials while abscissæ represent intervals of time. Curve 20 illustrates the wave of fundamental frequency and corresponds to the component of fundamental frequency transmitted from the harmonic producer 3 to the grid 8 or it may represent the wave transmitted from source 1 of the harmonic producer 3.

Wave 21 of three times the fundamental frequency is transmitted from the harmonic producer 3 simultaneously with the wave 20 and is in such phase relation with respect to the wave 20 that a maximum or crest in the wave 20 occurs simultaneously with a maximum or crest of like sign occurring in the wave 21, thereby producing a resultant wave 22 having a series of sharp peaks 23 remote from the zero axis of the wave. The zero axis of the waves corresponds to the E. M. F. of the polarizing source 7.

The polarizing E. M. F. 7 is made so large that no substantial amount of space current can flow through the output circuit 10 until the grid potential, varying in accordance with the wave 22, is in excess of that indicated by the dotted line 24. It will thus be seen that on the rising slope of the wave 22 the amplifier 6 suddenly becomes conducting, being a maximum at the point 23 and then suddenly returns to a non-conducting condition on the downward slope of the wave upon reaching the point corresponding to the dotted line 24, this process occurring once during each cycle of the fundamental wave 20.

Wave 22 is made of such intensity that the potential corresponding to the point 23 produces a minimum impedance through the tube 6. As a result of the rapid change in conductivity of the tube 6 from zero to a maximum, and vice versa, or in other words, of the variation in resistance from a maximum to a minimum, and vice versa, the loss of energy in the tube 6 is reduced to a minimum, the period of time during which the loss in the tube is large being negligible, or very small, depending upon whether the rate of change of grid potential is, respectively, more or less abrupt.

Fig. 3 shows a source of complex control waves 30 to transmit waves of fundamental frequency f , and of second harmonic frequency $3f$, through the inductive coupling

31 to the grids 32, 33 of the amplifier tubes 34, 35 arranged as a balanced amplifier having an input circuit 36 and an output circuit 37. The source of polarizing potential 38 maintains grids 32 and 33 at such a high negative potential as to prevent the flow of any substantial amount of space current from the source 39. The windings of transformer 31 are so poled as to apply components of potentials of opposite sign to grids 32, 33.

Waves set up in output circuit 37 are transmitted by means of the transformer or inductive coupling 40 to the tuned circuit 41 which contains the inductance 42 and variable capacity 43, together with the inductance and capacity introduced in the circuit 41 by means of the coupling 40, and from other sources. Circuit 41 is adjusted to resonance with the waves of fundamental frequency by means of the variable capacity 43. Resistance 44 represents the resistance of the load to which the waves flowing through the circuit 41 are subjected.

The complex wave from the source 30 has approximately the same shape as curve 22, Fig. 2. The zero axis of the waves in this case corresponds to the E. M. F. of the polarizing source 38. During the first half cycle of wave 20, the wave 22 contains the peak 23 which is applied as an impulse of positive potential to the grid 32, and is then followed in the succeeding half cycle of wave 20, by a second peak 23 which is applied as an impulse of positive potential to the grid 33.

Similarly, a positive peak is applied to first grid 32 and then grid 33, during each cycle of the fundamental wave 20.

The dotted line 24 represents the critical potential of the grid 32 above which space current begins to flow through the tube 34 from the source 39, while dotted line 25 represents the critical potential of the grid 33 which is of such value that potentials more removed from the zero axis of the wave than the dotted line 25 produce space current through the tube 35 from the source 39. It will thus be seen that during one half cycle of the wave 20, space current rapidly builds up in the tube 34 until the tube becomes of minimum impedance, the current being then suddenly reduced to zero. During the succeeding half cycle of the wave 20, space current builds up suddenly in the tube 35 and then is suddenly reduced to zero. A similar flow of space current occurs in the tubes 34 and 35 during subsequent cycles.

The windings of the transformer 40 are so poled that a space current impulse through the tube 34 produces an opposite effect in the work circuit 41 from that produced by a space current impulse through the tube 35. During each cycle there are therefore produced two impulses through

the output circuit 37 and the work circuit 41, one of said impulses being opposite in sign from the other impulse. These impulses set up waves of fundamental frequency which are stored up by resonance in the work or load circuit 41. Inasmuch as energy is supplied to the circuit 41 twice during each cycle, the current flowing through the resistance 44 is maintained more constant than would be the case if one of the impulses were omitted, for example, as in work circuit 12, Fig. 1. The source 30 may consist of the elements 1, 2, 3, shown in Fig. 1.

Fig. 4 shows an oscillator operating in a manner similar to that of the circuit shown in Fig. 3. In this case, space current impulses transmitted alternately through the tubes 34 and 35 are supplied through the transformer 40 to the work circuit 50 which is adjusted to resonance with the fundamental frequency by means of the capacity 51. In addition to waves of fundamental frequency, set up in the work circuit 50, waves of harmonic frequency are also produced, among these being waves of second harmonic frequency.

The variable resistance 52 is provided to adjust the phase relation between the fundamental and second harmonic waves, these waves being transmitted by means of the transformer 53 through the feed-back circuit 54 and through the transformer 31 to the input circuit 36.

Feed-back circuit 54 contains the tuned, or anti-resonant circuit 55 adjusted approximately to resonance with the wave of fundamental frequency by means of variable inductance 56 and variable capacity 57 for the purpose of adjusting the amplitude of the fundamental wave with respect to that of the second harmonic wave.

The amplitude of the fundamental wave in the feed-back circuit 54 is increased by detuning the circuit 55 and decreased by tuning circuit 55 more closely to resonance with the fundamental wave. Capacity 58 permits of adjusting the capacity reactance of the circuit 54 to be equal to that of the inductive reactance at the second harmonic frequency, thus providing a low impedance to the second harmonic wave.

In general, the feed-back circuit 54 attenuates the fundamental wave transmitted to the input circuit 36 relatively more than the second harmonic wave in order to provide the desired relative amplitudes for these waves, the relatively greater attenuation of the fundamental wave being due to the higher impedance of the circuit 54 to this wave.

Variable resistance 59 is provided to control the phase relation between the fundamental and second harmonic waves as well as controlling the amplitudes of these waves.

Waves of fundamental frequency besides having the relation shown in Fig. 2 to waves of second harmonic frequency are adjusted by means of either or both of the phase adjusting resistances 52 and 59 so that the control wave 22 transmitted through the feed-back circuit 54 and impressed upon the tubes 34 and 35 produces a flow of space current which generates a wave in the work circuit 50 in exact synchronism with the wave already set up therein. In other words, the time occurring between two successive positive peaks impressed upon the grid of the tube 34 is made exactly equal to that of the period of the fundamental wave 20.

Work circuit 50 includes the transformer 60 which transmits waves to the filter 61 designed to pass waves of desired frequency, such as the fundamental waves, to the exclusion of other waves in the circuit 50. A load to be supplied with the desired waves such as those of fundamental frequency, may be connected to the terminals 62. Filter 61 may be designed in accordance with the disclosure in United States patent to G. A. Campbell No. 1,227,113.

Fig. 5 is similar to Fig. 4, but shows two feed-back circuits 65 and 66 in place of the single feed-back circuit 54 in Fig. 4. Work circuit 50 is coupled to feed-back circuits 65 and 66 by means of transformer 67 while feed-back circuits 65 and 66 are coupled to the input circuit 36 of the balanced amplifier 34, 35 by means of the transformer 68. Feed-back circuit 65 is designed to transmit waves of fundamental frequency and contains the filter, network, or tuned circuit 69 designed to pass waves of fundamental frequency and suppress waves of other frequencies.

In the case where the element 69 is a filter circuit, a sufficient number of sections may be provided to adjust the phase of the fundamental wave component to be impressed upon the input circuit 36 so that the waves impressed upon the input circuit 36 will be in proper phase relation to the waves already set up in the work circuit 50. Resistance 70 permits of adjusting the amplitude of the fundamental wave to the desired value.

Feed-back circuit 66 is designed to transmit a wave component of second harmonic frequency and contains the filter network or tuned circuit 71 designed to pass waves of second harmonic frequency and suppress waves of other frequencies. Element 71 consists of a filter, the number of sections of which may be so chosen that the second harmonic wave is adjusted to the proper phase relationship with respect to the fundamental wave transmitted to the input circuit 36, or in other words, to provide the approximate relationship indicated between waves 20 and 21 in Fig. 2. Variable resistance 72 permits of adjusting the second

harmonic wave to the desired amplitude. Filters 69 and 71 may be constructed similarly to filter 61, Fig. 4. The term balanced amplifier as used in the specification and 5 claims is intended to designate an amplifier of the space discharge type having two space current paths and control elements therefor connected in opposite sense with respect to the potentials applied thereto.

10 Many variations may be made in the specific arrangements of the above circuits and in the methods of operating them without departing from the broad features of the invention disclosed.

15 Features of the invention believed to be novel are pointed out in the appended claims.

What is claimed is:

1. In a generator of electric waves, an 20 amplifier of the space current type having two space current paths and control elements therefor connected in opposite sense with respect to the potential applied thereto, input and output circuits for said amplifier, 25 means associated with said input circuit to normally prevent transmission of any substantial amount of space current through said output circuit, a source of waves having a component of fundamental frequency and 30 various components harmonically related thereto associated with said input circuit, means for causing the crests of certain of said components to occur at the same time to cause space current to be transmitted 35 alternately through one and then the other of said paths, and a work circuit associated with said amplifier output circuit.

2. In a generator of electric waves, an 40 amplifier having two space current paths and control elements therefor connected in opposite sense with respect to the potential applied thereto, an input and an output circuit therefor, a source of waves having a component of fundamental frequency and of 45 three times the fundamental frequency coupled to said input circuit, means for causing the crests of said components to occur at the same time, means associated with said input circuit to prevent the transmission of any 50 substantial amount of space current through said amplifier during a portion of each cycle of said fundamental wave, and a work circuit associated with said amplifier output circuit.

55 3. In an amplifier having two space current paths and control elements therefor connected in opposite sense with respect to the potential applied thereto, an input and an output circuit therefor, the method of 60 generating oscillations in said output circuit which comprises impressing a polarizing potential upon said input circuit to normally prevent the transmission of any substantial amount of space current through said 65 output circuit, and applying to said input

circuit a wave comprising a component of fundamental frequency and various components harmonically related thereto the crests of which occur at the same time to produce sudden space current impulses in 70 said output circuit.

4. In an amplifier having two space current paths and control elements therefor connected in opposite sense with respect to the potential applied thereto, an input and 75 an output circuit therefor, the method of generating oscillations in said output circuit which comprises impressing a polarizing potential upon said input circuit to normally prevent the transmission of any substantial amount of space current through said output circuit and impressing a wave comprising a component of fundamental frequency and a second harmonic component of the fundamental frequency, the crests of 80 one of said components occurring at the same time as the crests of the fundamental to produce sudden impulses in said output circuit.

5. In a generator of electric waves, an 85 amplifier having input and output circuits, a work circuit associated with said output circuit, and, coupled between said work and input circuits, a single feed-back circuit resonant to a wave of harmonic frequency and containing a circuit substantially anti- 90 resonant to a wave of fundamental frequency for adjusting the relative amplitudes of the fundamental and harmonic frequency waves.

6. In a generator of electric waves, an 100 amplifier having two space current paths and control elements therefor connected in opposite sense with respect to the potential applied thereto, input and output circuits therefor, and means associated with said circuits to feed back a peaked wave comprising a wave of fundamental frequency and various components harmonically related 105 thereto having their crests occurring at the same time from said output to said input circuit.

7. In a generator of electric waves, an 110 amplifier having two space current paths and control elements therefor connected in opposite sense with respect to the potential applied thereto, input and output circuits therefore, a tuned work circuit associated with said output circuit, and means coupled between said work and input circuit to feed back a peaked wave comprising a wave of 115 fundamental frequency and various components harmonically related thereto and having their crests occurring at the same times as those of the fundamental wave from said work circuit to said input circuit.

8. In a generator of electric waves, an 120 amplifier having input and output circuits, and means coupled between said circuits to feed back a plurality of wave frequencies 125 from said output circuit to said input cir- 130

cuit and to adjust the time of occurrence of crests in one of said waves to coincide with the crests in another of said waves.

9. In a generator of electric waves, an amplifier having input and output circuits, a single feed-back circuit coupled between said output and input circuits to transmit a plurality of wave frequencies between said output and input circuits, and means in said feed-back circuit to adjust the phase of said input wave with respect to waves in said output circuit.

10. In a generator of electric waves, an amplifier having input and output circuits, a single feed-back circuit coupled between said output and input circuits to transmit a plurality of wave frequencies between said output and input circuits, and means in said feed-back circuit to adjust the relative amplitudes of the waves transmitted therethrough.

11. In a generator of electric waves, an amplifier having input and output circuits, a single feed-back circuit coupled between said output and input circuits to transmit a plurality of wave frequencies between said output and input circuits, and phase shifting and amplitude controlling means in said feed-back circuit.

12. The method of producing oscillations which comprises producing a complex wave consisting of components of fundamental and second harmonic frequency in such phase relation that each crest in said fundamental wave occurs at substantially the same time as a crest of like sign in said harmonic wave, said crests forming peaks in said complex wave, amplifying only that portion of each peak which is remote from

40 the zero axis of said complex wave whereby a complex output wave is generated, and

selecting a wave of fundamental frequency from said output wave.

13. The method of producing oscillations which comprises producing a complex wave consisting of components of fundamental and harmonic frequency in such phase relation that each crest in said fundamental wave occurs at substantially the same time as a crest of like sign in said harmonic wave, said crests forming peaks in said complex wave, amplifying portions of said complex wave lying on opposite sides of the zero axis of said complex wave whereby a complex output wave is generated, and selecting a wave of fundamental frequency from said output wave.

14. In a generator of electric waves, an amplifier having input and output circuits, associated with said output circuit a tuned work circuit, in which wave components of fundamental frequency and harmonically related thereto are produced, including means for controlling the relative phases of said components to produce a peaked wave, and means coupled between said work circuit and said input circuit to feed back said peaked wave.

15. In a generator of electric waves, an amplifier having an input and output circuit, a single feed-back circuit coupling said output and input circuits to transmit a plurality of wave frequencies therebetween, said feed-back circuit being resonant to one of said frequencies and including a circuit substantially anti-resonant to another of said frequencies.

In witness whereof, I hereunto subscribe my name this 11th day of January, A. D. 1922.

CLARENCE A. SPRAGUE.
